UNITED STATES PATENT OFFICE.

WILLIAM ERASTUS WILLIAMS, OF WILMETTE, ILLINOIS.

RAILWAY-CAR ROOF.

Application filed February 15, 1926. Serial No. 88,229.

My invention relates chiefly to freight box car roofs but may be employed for other structures. The object of my invention is to provide a very strong, cheap, durable roof and one that will stand all kinds of service without tearing or rupturing by the winding and twisting of the body of the box car due to uneven loading and to variations in the track surface, and at the same time make a roof that does not require an internal sheathing for the support of the rain shedding sheet. Further, to make a roof that can be adapted to be used with a lightweight sheet over ordinary carlines used in the framing of the box car.

Further, my invention also has for its object a desirable and efficient fastening for the running board saddle onto the roof body of the car.

Reference will be had to the accompanying drawings in which Fig. 1 is a transverse elevational section of the roof of a car showing the roof sheet on section 1—1 of Fig. 10.

Fig. 2 is a plan of a portion of the roof across the car.

Fig. 3 is a plan view on a larger scale of the left end of what is shown in Figs. 1 and 2 where the carline and the roof sheet join the sideplate.

Fig. 4 is a vertical sectional elevation on line 1—1 of Fig. 10 through the eave section only of the car.

Fig. 5 is a similar view to that of Fig. 4 but showing a modified form of sideplate construction.

Fig. 6 is an edge elevational view of my roof sheet.

Fig. 7 is a plan view of the roof sheet on a larger scale than that shown in Fig. 6 and 40 with a part of the roof broken out in order to get both ends of a sheet within the figure.

Fig. 8 is a section on line 8—8 of Fig. 6.

Fig. 9 is a central transverse section on line 9—9 of Fig. 6.

Fig. 10 is a transverse view from carline to carline substantially on line 10—10 of Fig. 1.

Fig. 11 is a sectional elevational view transversely of the running board and with 50 the roof sheet extending to what is a view from the right end of Fig. 10.

Fig. 12 is an elevational cross-section showing a wooden running board saddle.

Fig. 13 is an elevational cross-section through the running board showing the 55 parts that are shown in Fig. 12 when wooden running board saddle is used.

In the drawing, see Fig. 4, the sideplate construction of the car is shown as a Z-bar having the lower extending leg 2 inside 60 which the framing and sheathing of the car is fastened so that this leg 2 becomes the eave of the car in this form of construction. The web of the Z-bar indicated by 3 lies horizontally and forms a part of the roof 65 sheathing surface, the vertical leg 4 of the Z-bar extends upward and the carlines and the roof sheets are fastened to this leg, being, as it were, the modern standard adopted for freight car construction.

With my type of car roof and some other types of roofs there is provided an angle 5 secured by rivets 6 to the leg 4 of the Z-bar sideplate. The outwardly extending leg 7 of the angle 5 furnishes a means for securing the body of my roof sheet to the sideplate of the car. A specially constructed Z-bar, is shown in Fig. 5, which seeks to provide a sideplate of Z-bar construction having the horizontal web 8 inclined for better shedding of the water than is shown by the standard Z-bar having the horizontal web 3 of Fig. 4. With the Z-bar shown in Fig. 5 a flange 9 is made integral with the body of the Z-bar and thus dispenses with 80 the angle 5 in the use of a roof of a type which requires a carline having an outward extending leg.

I prefer to make my carlines of I-beam section having the web 10, lower flange 11, 90 and upper flange 12, and providing the I-beam at each end with a knee brace piece having stiffening flanges 13 and having vertically arranged web 14, and an inclined web 15 which latter web is underneath the 95 lower flange 11 of the I-beam carline.

The web 14 of this angle knee brace piece is riveted by rivets 16 through the upwardly extending leg 4 of the Z-bar sideplate and the inclined web 15 is riveted by rivets 17 to 100 the lower flange 14 of my I-beam carline. In addition to riveting the web 15 to the lower flange 11 of the I-beam carline I strike up projections 18 out of the metal of the web 15 and these projections extend up 105 through slots or apertures in the lower flange

11 of the I-beam and are turned over and become, as it were, additional rivets to secure the carline to the sideplate.

The upper flange 12 of the I-beam is curved downwardly at each end and passes across and below the lower flange 14 and terminates in a downward end 19 see Fig. 4. This curving downward of the upper flange 12 of the I-beam is brought about in two ways; one of them by cutting off the lower flange 11 and web 10 shorter and then swaging down the web to permit of the shape shown in the drawings but in place of this swaging down operation I prefer to cut away the web in a curved form in the shape desired to permit a bending down of the flange 12 to the position 19 as desired. The roof or covering sheet itself is made of a galvanized steel sheet pressed into form as best illustrated by Figs. 7, 8, and 9 and the sheet extends from eave to eave of the car in an arched curved form. This sheet is shown in plan of Fig. 7 wherein there is a central swell or bulge corrugation 20 which is at its maximum height in the middle of the car as shown by the sectional view, Fig. 10, and this bulge or corrugation, as some might prefer to call it, tapers off in the curved marginal portion 21 and terminates at 22 while the valleys 23 on each side retain the arch corresponding to approximately the lower flange 11 of the I-beam carline and thus the valleys 23 will rest on the ridge-pole as indicated in Figs. 10, 11, 12, and 13. Likewise, when purlins are used these valleys will rest on the purlins. However, the arch form and the depth of this corrugation or bulge 20 as compared to the valleys 23 are such that the roof sheet itself will sustain itself from carline to carline because of the inherent strength of this form. The line load capacity of each sheet depends of course, on the thickness of metal that is used for this sheet. The edges of the sheet at the central portion of the roof and extending on each side thereof for about half the distance between the running board and the carline is shown in Fig. 9 wherein there is the flange 24 which rests on the top of the upper flange 12 of the I-beam carline and there is a small inwardly projecting swell or curved inward projecting portion 25 which extends underneath this upper flange 12 of the I-beam carline. This portion 25 is in full form on each side of the centers but approximately at the points 26, see Fig. 7, it begins to fade out or merges at approximately the points 27 into the straight portion 28 as indicated in Fig. 8 the flange 24 remaining the same.

In the assembling of the roof sheets upon the carlines these inwardly projecting curved portions 25 are sprung down past the edges of the upper flange 24 of the adjacent I-beam carlines and owing to the peculiar

shape and depth of the bulge or crown 20 and the valleys 23 the roof sheet will spring this amount without permanent damage to itself.

At the ends 29 of the roof sheet there is turned downwardly the vertical flange 30, see Fig. 6, and after the roof sheet is assembled onto the carlines and the sideplate, this flange 30 is hammered under as shown by 31, Fig. 4. This undeturned portion may extend as desired the whole width of the sheet or only between the points 32 and 33 in Fig. 7 and it will be noticed that between the points 32 and 33 and the edges 34 and 35 the roof sheet extends out a little further than the portion between the points 32 and 33.

The purpose of this arrangement is, that when a car body is given a serious twist or wind due to eccentric loading or wide variation in the track surface the one sideplate will travel ahead or backward from a true opposite position and thus bring about a sort of diagonal arrangement of the roof sheet across the car. This diagonal movement, of course, is slight but sufficient to rupture the roof in some instances where the corners or edges 34 and 35 are secured to the sideplate. Thus, there is a little tearing strain on the turned down flange 30.

The flange 24 of the roof sheet terminates at each end as is indicated by 36 and thus this flange is absent over the curved ends of the upper flange 12 of the I-beam carline.

The reason for the omission of this flange over this curved end is to allow a clearance for a secure fit of the flange 24 of the roof sheet into the main body of the carline without the necessity of an exact fit over the curved nose of the ends of the carline.

On the top of the upper flange 12 of the I-beam carline and over the flanges 24 of the roof sheet there is a cover strip 37 having a normal cross-section as shown at the left of Fig. 10 with downward extending flanges 38. These flanges 38 are retained in the shape shown in Fig. 10 from that portion of the carline from points 27 outward to the eaves while over that portion of the carline body and the roof sheet where is the curved portion 25, these flanges 38 are bent inward as indicated by 39 at the right of Fig. 10. This bending inward of the flange 38, of course, taking place after assembling of the carlines and roof sheets. This cover plate 37 extends over the ends of the carline downwardly as shown in Figs. 3 and 4 having the vertical portion 40 secured by rivet 50 through the lower end 19 of the upper flange 12 of the I-beam carline. The flange 38 of the cover plate 37 is curved over at the ends of the carlines as indicated by line 41, Fig. 4, while the edge of the roof sheet minus the flange 24 is curved as indicated by 42, see Fig. 6 and

- shown in a dotted line in Fig. 4. Thus the flange 38 of the cover plate 37 extends over the entire edge of the roof sheet from eave to eave and the roof sheet is held down in the center of the car not only by the portions underneath the upper flanges 12 of the I-beam, but also by the fastenings of the running board saddle to the carline. While at the eaves the cover plate 37 is secured to the ends of the carlines by rivets 50 thus holding down the roof sheet at its edges at the eaves of the car while the curved over flange 31 also holds the body of the roof sheet down onto the sideplate.
- 15 I secure the ridgepole 43 to the lower flange 11 of the I-beam carline by bolts 44, see Fig. 10.
- The running board 45 is secured by a compound fastening composed of 3 pieces comprising suitable attaching bolts 46, an iron plate 47 and a U-shaped bracket 48 united thereto by rivets 49. This bracket 48 has a lower leg 63 secured by bolts 51 through both flanges of the I-beam and through the cover plate 37. In order to prevent leakage around the bolt holes through which these bolts 51 pass there is provided a packing piece of asphalt felt 52 lying underneath the portions 63 of the U-shaped bracket 48. Not only that, underneath the heads of the bolts 51 I place a metal washer 53 on top of a soft metal washer 54 so that as bolt 51 is tightened the soft metal washer will make a close fit into the lower leg 63.
- 35 Thus I insure against leakage around the bolt hole passageway.
- In order to enter the bolts 51 I provide an aperture 55 in plate 47 and bracket piece 48 which aperture 55 is covered up by the running board 45.
- Underneath that portion of the cover plate whereat there is fastened the running board saddle I provide a metal filler strip 56 see Fig. 10 which is slightly thicker than the thickness of the flange 24 of the roof sheet so that the main strain of holding the running board saddle onto the carline is taken up by this filler strip 56.
- 50 Thus provision is made for a slight longitudinal yielding movement along the length of the carline by the edge of the roof sheet before the roof sheet itself will tear which may be due to an extreme twist or wind in the car body. However, the spring of the roof sheet itself is all that is normally needed to take care of any twist or wind of the car body due to unequal loading or variations in the track surface and this spring of the sheet is permitted to take place by the peculiar shape of the roof sheet itself. When it is desired, to use a wooden running board saddle this sort of a saddle is shown in Figs. 12 and 13 wherein there is a wooden block saddle 57 which saddle straddles the cover plate 37 and the carline underneath it has
- projections down the sides indicated by 58. The block is riveted across by rivets 59 to prevent splitting and is secured to the carline by means of the bolts 60 passing through with their nuts on the inside of the car. 70 The heads 61 of these bolts are in little recesses in the top of the block 57 and these recesses are filled with asphalt pitch after the bolts are in place which together with the covering of the running board 45 thus 75 prevents leakage down, through, and around the bolt holes to the inside of the car, the running boards being secured to the saddle block 57 by the bolts 62.
- 80 In place of the saddle here shown, any suitable running board saddle may be applied with my roof sheet and carline.
- The relatively deep valleys and deep middle or central bulge of my roof sheet are substantially corrugations of wide area and 85 relatively deep as relates to each other as compared to corrugated iron generally and thus the sheet may be compressed across its width somewhat in the manner in which a coiled spring might be compressed or stretched as 90 will be observed from the contour of the sheet as shown in Fig. 10. When the body of the car is twisted by uneven loading or uneven track surface the sideplates do not lengthen or shorten as between the spaces 95 of the carlines and thus no variation in the distance of the width of the sheets takes place in the ends of the sheet at the location of the sideplates but when the carlines, as it were, swing in advance of a true right 100 angular position as relates to the other side of the car then there does take place a compression in the width of the roof sheet or the shortening of the distance between the carlines as compared with a direct longitudinal line and this compresses the roof sheet 105 across its width and in this movement one end of the roof sheet is made to travel forward or backward as relates to the other end and produces, as it were, a hinged action of the end of the roof sheet at the sideplate. Where the end flanges of my carline turn down vertically over the edge of the sideplate there would then be danger of the 110 tearing of the roof sheet at the corners of the roof sheet on the sideplate. By making my flange 30 with clearance at each edge and fitting the sideplate at the middle of the sheet and with clearance at each end there is permitted this hinge motion without 115 danger of rupturing the roof sheet.
- 120 Thus, by the springing of the main body of the roof sheet and this hinging action at the sideplates I secure a safe roof against the tearing of the roof sheet through the 125 twisting action of the body of the car and at the same time provide a snug fit of the edges of the roof sheet with the edges of the carlines.
- I have disclosed novel features in this ap- 130

plication which are also disclosed in my co-pending applications Ser. Nos. 86,817 and 96,529, and I expressly reserve the right to claim any novelty disclosed, but not claimed, 5 herein in another co-pending application.

I claim—

1. In a roof of the class described, the combination with a car provided with carlines and sideplates, of a roof sheet extending transversely of the car and having a relatively high central bulge portion, a relatively deep valley portion on each side thereof and having its edges curved upwardly and provided with flanges extending horizontally and adapted to rest on top of the carlines, the ends of the sheet in the region of the sideplates terminating in a relatively flat surface as relates to the bulge, valleys and turned up edges of the sheet, the end flanges projecting downward over the edge of the sideplate at each end of the roof sheet.
2. In a roof of the class described in combination with two sideplates, a roof sheet extending over the edge of a sideplate and provided with a downwardly projecting flange, said flange fitting closely to the edge of the sideplate in the middle portion of the roof sheet there being a clearance space between the edge of the sideplate and said flange at each corner of the roof sheet.
3. In a roof structure of the class described, the combination with two sideplates, of one or more carlines resting on the top of the sideplates and having its ends curved downward in a rounded form over the edges of the sideplates, a roof sheet having relatively deep valleys and a central bulge extending parallel with said carline whereby the main body of the sheet may be sprung wider or narrower by bending action of the body of the sheet lengthwise of the sheet, substantially on the principle of a coiled spring, the said sheet having horizontal flanges extending on the top of the carline and the upturned edges of the sheet adjacent to the carline fitting closely between adjacent carlines and a cover plate covering the horizontal flanges of the roof sheet and extending over the carlines and curved downward over the end of the carline.
4. In a railway car provided with a sideplate, a roof sheet of the class described, having a turned over flange extending over the outer edge of the sideplate and said flange fitting the vertical edge of the sideplate in the middle portion of the sheet and spaced from the sideplate at each edge of the sheet.
5. In a car roof structure the combination with one or more I-beam carlines each having its web vertically arranged of a roof sheet having upturned edges approximating the depth of the carlines and also a central bulge portion substantially parallel with the carline and of a depth approximating the depth of the carline and the said upturned edges of the roof sheet having horizontal flanges resting on the top of the carlines and a cover plate covering the carline and the upturned edges of the roof sheet, the said cover plate secured to the carline at the eaves portion of the car and at the running board region.
6. In a roof structure of the class described having one or more carlines, a roof sheet having upturned edges terminating in horizontal flanges the said flanges extending over the top of the carline for a short distance in combination with a filler strip on the top of the carline and between the horizontal flanges of the roof sheets the said filler strip being slightly thicker than the thickness of the flanges of the roof sheet and lying between the flanges and across the region underneath the running board saddle for the purpose of making a positive solid connection of the running board saddle with the top of the carline.
7. In a roof structure having carlines, roof sheets having edges lying on top of the carlines and a cover plate over each of the carlines and edges of the roof sheets, a running board saddle composed of a metal plate supported on brackets each of said brackets being bolted to the top of a carline by bolts passing through a cover plate, a strip lying between each of the cover plates and the top of the carline and extending between said edges of the roof sheets, said strip being thicker than the metal of the edges of the roof sheets.
8. In a roof, the combination with carlines, of a plurality of roof sheets, each of said sheets having lateral flanges terminating at a distance from each end of the sheet and supported on a top flange of a carline, a filler strip thicker than said roof sheet flanges interposed between the edges of adjacent roof sheets, a cover plate enclosing an edge of each of two adjacent sheets, the said filler strip and the top flange of a supporting carline, and a running board saddle secured to said carlines by bolts passing through holes in said cover plate and filler strip.
9. In a car roof, the combination with one or more I-beam carlines having vertically arranged webs, a pair of sideplates co-operating with said carlines to form a roof frame, a plurality of roof sheets each fitting snugly between adjacent carlines and having a lateral flange overlapping a portion of an upper flange of a carline, a central portion of each edge of said sheets curved under an edge of a roof frame member, and each sheet curved downwardly and away from the adjacent carline to provide a relatively deep valley.
10. In a roof structure one or more car-

- lines having a normally flat surface at the summit thereof and curved downwardly near each end, a roof sheet having a central bulge portion, lateral flanges resting on the top of the carline and a curved portion extending downward into a relatively deep valley on the side adjacent to the carlines and the ends of the said roof sheet likewise curved downwardly and near the margins merging into an approximately flat surface over each side-plate.
11. In a car roof structure of the class described a carline, a roof sheet having upturned edges terminating in horizontal flanges resting on and fitting to the top corners of the carlines, the ends of the carlines curved downward at the eaves of the car and the said horizontal flanges of the edges of the roof sheet cut away at the curved ends of the carlines.
12. In a roof structure of the class described, a plurality of roof sheets and carlines, said roof sheets having upturned edges of a width between the said edges substantially the width between adjacent edges of the carlines said roof sheets provided with a central bulge portion and deep valleys running across the car and adapted to be sprung transversely of the roof sheet and rigidly secured to the car at the central portions of the said edges only to accommodate by spring action the winding and twisting of the body of the car.
13. In a roof of the class described having carlines and roof sheets, said roof sheets furnishing the full covering for the car without interior sheathing and provided with horizontal flanges extending on the top of the upward corners of the carlines and provided with a valley at each edge of the roof sheet adjacent to the carline and with a central upward corrugation of a distance of relative, considerable depth adapted to allow for contraction and expansion by the springing action of the sheet itself across its width each of said sheets being provided with down turned terminal flanges, said flanges extending down over the edge of the sideplate and fitting the edge of the sideplate in the middle portion of the roof sheet and with clearance at the corners of the roof sheet.

Signed at Chicago in the county of Cook and State of Illinois this 11th day of February, 1926.

WILLIAM ERASTUS WILLIAMS.
